UNITED STATES PATENT OFFICE

136,410

DESIGN FOR A COMBINED WASHER AND WRINGER DRIVE HOUSING

Merlin M. Jackson, San Jose, Calif.

Substituted for abandoned design application
Serial No. 107,742, July 29, 1942. This application
March 18, 1943, Serial No. 109,776

Term of patent 3½ years

To all whom it may concern:

Be it known that I, Merlin M. Jackson, a citizen of the United States of America and a resident of the city of San Jose, county of Santa Clara, and State of California, have invented a new, original, and ornamental Design for a Combined Washer and Wringer Drive Housing, of which the following is a specification, reference being had to the accompanying drawing, forming part of this application, in which:

Figure 1 is a top plan view of a combined washer and wringer drive housing, showing my new design;

Figure 2 is a side elevational view of the same; Figure 3, an elevational view of one end thereof; and

Figure 4, an elevational view of the other end of the same.

This is a substitute for application, Serial Number 107,742, applicant's prior design application, filed July 29, 1942, now abandoned.

I claim:

The ornamental design for a combined washer and wringer drive housing, substantially as shown and described.

MERLIN M. JACKSON.
